US0D1035816S

(12) **United States Design Patent** (10) **Patent No.:** **US D1,035,816 S**
(45) **Date of Patent:** **** Jul. 16, 2024**

(54) **COMBINED FIREARM SUPPRESSOR CORE,
MOUNT BODY, TUBE, AND SPRING**

(71) Applicant: **Maxim Defense Industries, LLC**, St. Cloud, MN (US)

(72) Inventors: **Travis Bundy**, St. Cloud, MN (US); **Oddbjorn Eken**, Prestfoss (NO); **Jason Harper**, Meridian, ID (US); **Patrick Alfred Tamble**, Richmond, MN (US)

(73) Assignee: **Maxim Defense Industries, LLC**, St. Cloud, MN (US)

(**) Term: **15 Years**

(21) Appl. No.: **29/823,249**

(22) Filed: **Jan. 14, 2022**

(51) **LOC (14) Cl. 22-01**
(52) **U.S. Cl.**

USPC **D22/108**; D21/572; D21/573

(58) **Field of Classification Search**

USPC D21/572, 573; D22/108, 199

CPC F41A 21/30; F41A 21/325

See application file for complete search history.

(57) **CLAIM**

The ornamental design for a combined firearm suppressor core, mount body, tube, and spring, as shown and described.

DESCRIPTION

FIG. 1 is a top, front, right perspective view of a combined firearm suppressor core, mount body, tube, and spring in accordance with our new design;

FIG. 2 is a top, rear, left perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof; and,

FIG. 8 is a right side view thereof.

The broken lines immediately adjacent shaded areas represent the bounds of the claimed design. All broken lines are directed to environment and form no part of the claimed design.

1 Claim, 4 Drawing Sheets
